J. POTAPOFF.

LOCK.

APPLICATION FILED FEB. 14, 1913.

1,074,329.

Patented Sept. 30, 1913.

UNITED STATES PATENT OFFICE.

JOHN POTAPOFF, OF ARRAN, SASKATCHEWAN, CANADA, ASSIGNOR OF ONE-HALF TO
MICHAEL E. RIEBIN, OF VERIGIN, CANADA.

LOCK.

1,074,329.

Specification of Letters Patent.

Patented Sept. 30, 1913.

Application filed February 14, 1913. Serial No. 748,446.

To all whom it may concern:

Be it known that I, JOHN POTAPOFF, a subject of the King of England, residing at Arran, in the Province of Saskatchewan and

5 Dominion of Canada, have invented certain new and useful Improvements in Locks, of which the following is a specification, reference being had to the accompanying drawings.

10 This invention relates to new and useful improvements in locks and has for its primary object to provide a lock, the tumblers and locking bolt of which are both operated through the medium of a compound key.

15 Another object of the invention is to provide a lock of this character, the locking bolt of which may be retracted and projected without changing the position of the tumblers.

20 A still further object of the invention is to provide a key, consisting of tumbler operating part, and of a locking bolt retracting part, and to combine such parts in such a manner that they will not interfere with 25 each other in their operation.

A further object of the invention is the operation of a lock of this character which will possess advantages in points of efficiency and durability, is inexpensive of 30 manufacture and at the same time is simple in construction and operation.

With the above and other objects in view the invention consists in the novel features of construction and the combination and arrangement of parts hereinafter more fully described, pointed out in the claims and shown in the accompanying drawings in which,

Figure 1 is a front elevation of a portion 40 of a door having the invention applied thereto, the cover-plate being removed to disclose the interior mechanism of the lock. Fig. 2 is a sectional view on the line 2—2 of Fig. 1. Fig. 3 is a sectional view on the line 45 3—3 of Fig. 1. Fig. 4 is a detail perspective view of the combined key.

Referring more particularly to the drawings 1 indicates the lock casing, which may be of any suitable shape, but preferably of a 50 rectangular form as shown in the drawings, and 2 indicates the cover-plate thereof, by the removal of which, access may be had to the interior mechanism of the lock. The

lock may be attached to the inner side of the door as shown in Fig. 1, or may be placed into a mortise formed in the door.

Arranged within the casing and adapted to entirely fill the same are the blocks 3 and 4, which are provided on one side with a longitudinal groove 5, adapted for the reception of the locking bolt 6. Formed in one of the longitudinal edges of the blocks, and arranged at one end thereof, is the recess 7, said recess extending inwardly and terminating into a substantially rectangular shallow recess 8. Opening into the recess 8 is the semi-circular recess 9, which communicates with the usual key-hole 10.

Secured to one side of the casing and extending inwardly in the recess 7 is a spacing block 11, adapted to be arranged between the sliding tumblers 12, said tumblers being arranged upon each side of the spacing block and disposed between the ends of the blocks 3 and 4 and the sides of the block 11. Having their intermediate portions arranged in the openings 13 at the rear of the block 11 and their ends bent inwardly and adapted to engage in the recess formed in the rear end of the tumblers 12, are the springs 14, which are adapted to normally hold the tumblers into engagement with the locking bolt 6. The locking bolt 6, is provided on one of its longitudinal edges with the spaced recesses 15 adapted to receive the beveled ends 16 of the tumblers 12 to hold the locking bolt in its projected position. Secured to the inner ends of the tumblers 12 is an actuating plate 17, which is beveled off on one of its edges to form an engaging surface 18.

In Fig. 4 is shown the combined key which comprises the main key 19 which consists of the stem 20 having a bit 21 formed upon one end and a handle member formed on the other end. Slidably mounted upon the stem 20 is a sleeve 23 which is provided at one end with a bit 24 and having a thumb plate 25 formed upon the other end whereby the same may be easily manipulated.

In Fig. 1 I have shown the lock applied to the inner side of the door, in order to unlock the same, the main key 19 is inserted in the key-hole and passed through until the bit 21 is arranged in the recess 9. The key is then turned, the bit 21 engaging the

surface 18 of the plate 17 and forcing the tumblers 12 out of the recesses 15. The sleeve 23 is then inserted within the key opening, until the bit 24 is disposed above the locking bolt 6. The sleeve is then turned, until the bit 24 engages in one of the spaced recesses 26 formed in the locking bolt, the turning movement of the sleeve forcing the locking bolt inwardly, a second turn being necessary to retract the bolt so that its outer end is disengaged from the keeper 27, which is secured to the jamb of the door. In order to lock the door from the inside the operation as above described is simply reversed.

In order to unlock the door from the outside, the key 19 is inserted in the casing until the bit 21 is disposed above the locking bolt, the sleeve 23 is then inserted until the bit 24 engages with the surface 18 of the plate 17. The sleeve 23 is then turned, the bit 24 engaging the plate 17 to force the tumblers 12 out of the recesses 15, the key is then turned, the bit 21 engaging in the recesses 26 to retract the locking bolt, said key being turned twice around to entirely disengage the locking bolt from the keeper and to retract said bolt within the casing. It will be seen that when the locking bolt is in its projected position the inner ends of the tumblers 12 will be disposed in the recesses 15 and held securely in place by the tension of the springs 14.

While I have shown and described the preferred form of my invention, it will be obvious that various changes in the details of construction in the portions may be resorted to for successfully carrying my invention into practice without sacrificing any

of the novel features or departing from the 40 scope thereof.

What I claim is:—

A lock of the class described including a casing, a locking bolt arranged within said casing for sliding movement, blocks disposed within the casing and having longitudinal grooves formed therein to receive the locking bolt, said locking bolt being provided upon its longitudinal edges with spaced recesses, said blocks being provided 45 at their abutting ends with inwardly extending recesses and further provided with a shallow recess communicating with the first recess, a spacing block secured to one side of the casing and arranged within said 50 recesses, said spacing block having spaced openings formed therein, sliding tumblers disposed upon each side of said spacing block and having beveled ends adapted to engage within the recesses in the locking 55 bolt, springs having their intermediate portions arranged in the openings in the spacing block and their ends engaging the ends of the tumblers, an actuating plate connecting the inner ends of said tumblers and disposed in the shallow recess, one edge of said actuating plate being beveled off to provide an engaging surface and means engaging said plate to disengage the tumblers 60 from the locking bolt and means co-operating with the first means to actuate the locking bolt.

In testimony whereof I hereunto affix my signature in the presence of two witnesses.

JOHN POTAPOFF.

Witnesses:

M. F. REBIN,
E. N. VERIGIN.
